UNITED STATES PATENT OFFICE.

MARK E. FONTANA, OF SAN FRANCISCO, CALIFORNIA.

MACARONI DRIER.

Application filed May 16, 1922. Serial No. 561,466.

To all whom it may concern:

Be it known that I, MARK E. FONTANA, a citizen of the United States, residing at the city and county of San Francisco and 5 State of California, have invented certain new and useful Improvements in Macaroni Driers, of which the following is a specification.

My invention relates to the class of driers, 10 with reference especially to the drying of paste, particularly macaroni.

It is important in the drying of macaroni that it be subjected uniformly to the drying medium, and that provision be made for utilizing the humidity extracted from the more advanced product, by uniformly transferring it to the less advanced product, and, at the beginning of operation to supply humidity from an extraneous source until the first 20 mentioned supply becomes effective.

These are the essential objects of my invention, although further objects lie in the provision of novel structural features and details, by which successive batches of the 25 product are continuously received in the drier, carried through an extensive path therein, and successively discharged, while the heating medium, with its accumulated humidifying effect is caused to travel 30 through the drier in a direction the reverse of the travel of the product.

To these ends, my invention consists in the novel drier which I shall hereinafter fully describe, by reference to the accompanying drawings, in which—

Fig. 1 is a vertical section of my drier.

Fig. 2 is a top plan view of the same.

Fig. 3 is a side elevation.

Fig. 4 is an end view, enlarged, of one of 40 the product carrying trucks.

Fig. 5 is a side view of the same.

Fig. 6 is a view of a fragment of the carrier chain.

1 is a casing, interiorly divided by the partitions 2 into a plurality of chambers 3 successively communicating at top and bottom alternately. At the base of the first chamber, shown at the left in Fig. 1, is the entrance opening 4 and at the base of the last 50 chamber is the discharge opening 5.

In the top of the casing over each pair of chambers are controllable vents 6—Fig. 1, and similar vents, not shown, may be placed in the sides.

7 is an endless traveling carrier mounted 55 on sprockets 8, as shown by the dotted lines in Fig. 1.

The carrier is so disposed as to move up in the first chamber of the casing, down in the second, up in the third and so on until it 60 moves down in the last chamber and thence returns in the lower part of the casing, through the partitions, to the point of beginning, as clearly indicated in Fig. 1. The carrier is, as usual with devices of this nature, composed of two spaced parallel side chains, Fig. 3, a fragment of one of which is shown in Fig. 6, and comprising successive articulated links from which, at suitable intervals, project the truck-engaging pins 70 or studs 9.

In Figs. 4 and 5 is shown one of the trucks 10, for carrying the product. It comprises a frame having casters 11 and provided in some cases with dowel sticks 12 over which 75 the macaroni, indicated by 13 in Fig. 4, is hung, and in other cases merely open to contain the product in bulk, or in trays for short cuts, as indicated in Fig. 3. The special adaptation of the truck for use in the 80 drier lies in the provision of the bails 14, which are secured at their bases to each end of the truck and thence rise at an outward angle, as shown in Fig. 5, to their apices, which extend above and are spaced from the 85 truck ends.

It will now be seen by reference to Fig. 1, that when a truck is pushed into the drier through the entrance opening 4, a pair of opposite pins 9 of the carrier chains 7 will 90 rise up beside each end of the truck, and, engaging the apices of the outwardly inclined bails 14 will pick up the truck and carry it up in the first chamber and down in the second chamber and so on until finally said 95 truck is deposited upon the floor of the last chamber in registry with the discharge opening 5. Thereupon the pins 9 of the carrier chains lower away from the truck bails and proceed on their return course.

Thus successive trucks are carried through the drier.

Associated with the discharge opening 5 of the drier is an endless traveling chain 15 with pins 16 which engage behind the 105 truck and push it out through the opening.

The drying medium is preferably heated air. Referring particularly to Fig. 2—17 is

the air intake, provided with heating coils 18, and communicating with a blower 19 which delivers through its discharge pipe 19' the heated air into the lower portion of 5 the last chamber of the drier casing—Fig. 1. The course of the air, as indicated by the arrows in Fig. 1, is the reverse of the course of travel of the product trucks, and thus not only is the product exposed to a uniform 10 drying heat, but also the moisture extracted is carried backward through all the chambers, thus beneficially affecting the advancing product. To assist the drying air in its course, there is placed a second blower 20 15 (Fig. 2) the suction pipe 20' of which leads from one of the intermediate chambers 3, and its discharge pipe 20'' leads into the next chamber, as shown in Fig. 1.

A humidifying element from an extraneous 20 source, is also supplied at this point. In practice, I prefer steam for this purpose, and to supply it to the intermediate blower 20, there is a steam pipe connection shown at 22 in Fig. 2. This second blower, which 25 may be termed a "booster" not only serves to assist the flow of the drying medium, but also provides opportunity for introducing a humidifying effect from an extraneous source, which is of advantage when the 30 drier is first put in operation, and until the operation has proceeded far enough to utilize the moisture taken from the product, at which time the extraneous moisture may be shut off.

35 In Fig. 2, is indicated the driving mechanism, comprising a motor 23 with transmission connection 24 to a shaft 25. Associated with this shaft is a speed reducing element 26, and bevel gear transmissions 40 at 27 to drive the sprocket shafts 28.

In Fig. 1 is indicated at 29 the transmission to drive the push out chain 15.

I claim:—

1. A drier comprising a casing interiorly 45 divided into a plurality of chambers successively communicating at opposite ends, the first of said chambers having an entrance opening and the last of said chambers having a discharge opening; an endless traveling carrier within said casing, having a course through said chambers from said entrance opening to said discharge opening and return; receptacles for the product to be dried, adapted to be entered into the first 55 chamber and delivered from the last chamber through their respective openings; interengaging elements on said traveling carrier and said product receptacles adapted to pick up said receptacles and transfer 60 them through the chambers; means associated with the last chamber for forcing a drying medium through the chambers in a direction opposite to the direction of travel of the product receptacles, and auxiliary 65 means associated with an intermediate

chamber for assisting the flow of the drying medium.

2. A drier comprising a casing interiorly divided into a plurality of chambers successively communicating at opposite ends, 70 the first of said chambers having an entrance opening and the last of said chambers having a discharge opening; an endless traveling carrier within said casing, having a course through said chambers from said entrance opening to said discharge opening and return; receptacles for the product to be dried, adapted to be entered into the first chamber and delivered from the last chamber through their respective openings; interengaging elements on said traveling carrier and said product receptacles adapted to pick up said receptacles and transfer them 75 through the chambers; means associated with the last chamber for forcing a drying medium through the chambers in a direction opposite to the direction of travel of the product receptacles; and means intermediate 80 said first and last chambers for supplying a humidifying medium from an extraneous 85 source.

3. A drier comprising a casing interiorly divided into a plurality of chambers successively communicating at opposite ends, 95 the first of said chambers having an entrance opening and the last of said chambers having a discharge opening; an endless traveling carrier within said casing, having a course through said chambers from said entrance opening to said discharge opening and return; receptacles for the product to be dried, adapted to be entered into the first chamber and delivered from the last chamber through their respective openings; interengaging elements on said traveling carrier and said product receptacles adapted to pick up said receptacles and transfer them 100 through the chambers; means associated with the last chamber for forcing a drying medium through the chambers in a direction opposite to the direction of travel of the product receptacles; and means intermediate 105 said first and last chambers for supplying a humidifying medium from an extraneous 110 source.

4. A drier comprising a casing interiorly divided into a plurality of chambers successively communicating at opposite ends, the first of said chambers having an entrance opening and the last of said chambers having a discharge opening; an endless traveling carrier within said casing, having a course through said chambers from said entrance 120 opening to said discharge opening and return, said carrier having projecting pins at intervals; receptacles for the product to be dried, adapted to be entered into the first chamber and delivered from the last chamber 125 130

ber through their respective openings, said receptacles having supporting bails outwardly inclined, to adapt them for the automatic engagement and release of the pins 5 of the traveling carrier, whereby said receptacles are picked up, advanced and released; means associated with said last chamber for forcing a current of drying medium through the chambers in a direction the reverse of 10 the travel of the receptacles; and auxiliary means associated with an intermediate chamber to assist the flow of the drying medium.

5. A drier comprising a casing interiorly divided into a plurality of chambers successively communicating at opposite ends, the first of said chambers having an entrance opening and the last of said chambers having a discharge opening; an endless traveling carrier within said casing, having a 15 course through said chambers from said entrance opening to said discharge opening and return, said carrier having projecting pins at intervals; receptacles for the product to be dried, adapted to be entered into the first chamber and delivered from the last chamber through their respective openings, said receptacles having supporting bails secured to their ends and outwardly inclined therefrom, to adapt them for the automatic engagement and release of the pins of the traveling carrier, whereby 20 said receptacles are picked up at the entrance of the first chamber, advanced through all the chambers and released in the base of the last chamber; a traveling carrier associated with the base of the last chamber 25 adapted to engage the released receptacles and convey them out through the discharge opening; and means for supplying a drying medium to said casing.

In testimony whereof I have signed my 30 name to this specification.

MARK E. FONTANA

In testimony whereof I have signed my name to this specification.

MARK E. FONTANA
